HOWARD J. PEO, OF ROCHESTER, NEW YORK

GAME OF SKILL

Application filed October 22, 1930. Serial No. 490,493.

The present invention relates to game apparatus and consists in the combinations and arrangements of elements hereinafter described and particularly set forth in the accompanying claims.

The invention has for its purpose to provide a game of simple and attractive appearance, which may be played by anyone without requiring experience or previous knowledge, and wherein the elements of dexterity and skill are so balanced or designed that it may be repeatedly operated by one and the same person with ever increasing interest and reasonable uncertainty of result.

15 The invention further contemplates offering to the public an interesting and novel game to be played by one or more persons at the minimum possible cost—one cent per game—and which will in no way conflict with 20 the law respecting coin control machines, or in the least offend the moral sense of the public.

It is further proposed to offer an entirely new or novel apparatus which is so attractively designed in that it will be prominently displayed in the shops of merchants, or generally in places where people assemble and which will suggest or prompt those seeing it with a desire to play. The game may be operated with equal skill and enjoyment by 25 children or adults.

In the operation of the game skill is the essential factor which contributes to successfully playing and obtaining a high score. 35 The game board or playing surface is set vertical or upstanding and accordingly each ball for its complete traverse is at all times in full view for tracing by the player so that after projection or shooting he may foretell 40 with reasonable certainty the probable score of each play.

The simplicity of construction of the machine is such that it may be manufactured in quantities at reasonably small cost to the 45 end that any one with comparatively small capital may own and operate a number of the machines located at widely diverse points. No special mechanical skill is essential for keeping a number of the machines in perfect 50 working order at all times and each machine

is wholly self-contained and of such over-all dimensions that it will occupy the minimum space for transportation or where it is set up for playing.

The invention is shown by way of illustration in the accompanying drawings, wherein:

Figure 1 is a front elevational view of the machine complete.

Figure 2 a transverse sectional view thereof taken on the line 2—2 of Figure 1.

Figure 3 a rear elevational view with the back of the casing removed.

Figure 4 a detailed view in front elevation showing the coiled or spiral race-way and ball receiving pockets, and

Figure 5 a side elevational view of the part shown in Figure 4.

Referring to the construction in further detail and wherein similar reference characters designate corresponding parts in the different figures shown, the machine consists of a suitable casing 6 of sheet metal having preferably a wooden base 7 and top 8 which are so proportioned that the front or operating face of the machine is set upright and slightly inclined to the rear for easy playing and convenient inspection as shown in Figures 1 and 2.

The characteristic feature of the game is a coiled or spiral race-way which is formed by a channel or groove 9 in the front face of a plate 10 suitably secured within the casing. Said spiral race-way is provided with a tangentially disposed entrance 11 located on the right side of the machine, and at its lower or terminal end communicates with a magazine 12 from which the ball members 13 are separately shot through the race-way by the arm 14 of a projecting device to be further described.

The respective convolutions or divisions of the coil or spiral are closely assembled as shown in Figures 1 and 4, and the entire race-way covers the greater front portion of the machine and is in full view through the glass cover and ball retaining plate 15, which is suitably set within the casing by the metal frame-piece 16. In like manner the transparent plate affords a full and clear view of

the several ball receiving pockets 17 and the magazine 12 thereby permitting each operator to observe practically all positions in the entire trace of the balls as they are separately played.

5 Each of the coils of the game board is provided with an exit opening 18 (Figure 4) to receive the ball and direct its passage through a returning channel-way 19 formed in the casing piece 20 which is in turn secured to the rear face of the plate 9 (Figure 2). The several exit openings 18 are disposed in straight vertical alignment and substantially along a medial position at the front of the machine, and each of said openings 15 has indicia indicating a score value. Thus the innermost opening at the central coil 9 is designated "Out", the next adjacent is marked "50", the next "40", and so on to the outermost coil which has the value of "10". 20 That is to say, the exit openings of the respective coils have score values which are maximum and then decrease towards the periphery of the coil. And for each 25 exit opening 18 there is a corresponding pocket or receiver 17 which communicates therewith through its respective channel-way 19 as clearly illustrated in Figure 1. Thus in the playing of the game the ball which 30 passes through the innermost opening 18 finds its way to the corresponding pocket designated "Out", and in like manner the balls will pass from the openings "40", "30", "20", etc., and ultimately fall into the corresponding pockets 17 designated "40", "30", 35 and "20", etc.

It is proposed to use the machine with five balls though it will be understood of course any greater or lesser number may be employed for properly playing the game. However, it is believed the most satisfactory results are obtainable with the use of five balls. After each "game" the five balls are held in one or more of the pockets 17 by a shelf 21 which is normally maintained in its retaining 40 position (Figure 2) by the spring 22. Said shelf is provided with a cam element or lug 23 that cooperates with a releasing or slideable latch 24 mounted on the back of the plate 10. When the balls are released by the shelf 21 they fall into the inclined passageway 25 formed in the base of the plate 10 and by gravity run into the magazine 12 which communicates with the passage-way 25 as shown 45 in Figures 1 and 4.

The plate member 10 providing the spiral race-way 9, the channel-ways 11 and 12, pockets 17, and magazine 25, is cast as a separate piece, and together with the portion 50 20 constitutes a single unitary structure or article of manufacture.

The released balls are temporarily held within the channel-way 25 by a finger or bar 26 projecting through the opening 27 (see Figures 1 and 4) into the path of said

balls, and said bar is secured to and operates with the shelf 21 by connection with the lug 23 thereof. After release by the bar 26 the five balls run into the magazine 12 from which they are separately expelled or shot into the spiral race-way by the projecting bar 14 as already explained. Thus in Figure 1 three of the balls have already been "played" and two remain to be "shot".

70 The ball projecting member 14 is secured to a shaft 28 having a strong tension spring 29 and a finger piece or trigger 30. In operation the trigger 30 is depressed by any finger of the hand—preferably the thumb—and when released will fly back under the tension of the spring 29 causing the bar 14 to instantly strike the ball 13 with considerable force and cause the same to traverse the race-way for a distance commensurate with the power of the trigger-spring at the instant of its release.

75 The operation of the machine is effected by a suitable coin controlled mechanism shown in Figures 2 and 3, and comprising a dial plate 31 notched on its periphery to receive a coin—preferably a cent—and through which coin the cam portion 32 of the arm 33 is turned an angular distance against the tension of spring 34. The arm 33 is fixedly mounted on and serves to operate the shaft 35, which is journaled in the side walls of the casing (Figure 3) and an arm or yoke member 36 secured on the shaft 35 co-acts with the cam or lug portion 23 of the shelf 21 to release said shelf member and permit the balls to fall into the passage-way 25 when they have been played, and are collected in one or more of the pockets 17. In like manner a yoke-piece or arm 37, secured to the shaft 35 co-acts with the sear 38 of the trigger shaft 28 and when said sear is depressed the pawl 39 is freed to permit the shaft 35 to be turned under the tension of spring 34 and thereby restoring the shelf 21 to its normal or ball retaining position. This simultaneously removes the finger or bar 26 from the path of the balls collected and retained in the passage-way 25, and the balls thus released will run into the magazine as shown. A spring 40 normally keeps the pawl 39 in operative position with respect to sear 38 of the trigger or projecting device.

80 105 110 115 120 It is to be understood that I do not desire to limit myself to the precise details of construction and arrangement herein set forth, as it is obvious that various modifications may be made therein without departing from the essential features of the invention.

What is claimed as new is:

1. A game apparatus comprising an up-standing and flat spiral race-way having exit openings, channel-ways leading from said openings, pockets at the terminals of the respective channel-ways, and a ball member adapted to be projected along the race-way, 125 130

- and pass through one of said openings, substantially as set forth.
2. A game apparatus comprising a flat spiral race-way having exit openings in straight radial alinement, channel-ways leading from said openings, pockets in parallel relation at the terminals of the respective channel-ways, and a ball member adapted to be projected along the race-way, and pass through one of said openings, substantially as set forth.
3. A game apparatus comprising an up-standing and spiral race-way having exit openings, channel-ways leading from said openings, pockets at the terminals of the respective channel-ways, a transparent ball retaining plate overlying the coiled race-way and said pockets, and a ball member adapted to be projected through the race-way, substantially as set forth.
4. A game apparatus comprising a flat spiral race-way having a plurality of exit openings in straight radial alinement, said openings having indicia denoting different scores, receiving pockets communicating with said openings and having characters corresponding with the indicia of the exit openings, and a plurality of ball members adapted to be projected through the race-way, substantially as set forth.
5. A game apparatus comprising an up-standing and flat spiral race-way having a plurality of exit openings in straight radial alinement, said openings having indicia denoting different scores, receiving pockets communicating with said openings and having characters corresponding with the indicia of the exit openings, a transparent ball retaining and cover plate overlying the race-way and said pockets, and a plurality of ball members adapted to be projected through the race-way, substantially as set forth.
6. A game apparatus comprising a coiled race-way having a plurality of exit openings, passageways leading from said openings respectively, pockets at the terminal ends of said passageways, a releasable shelf closing the ends of said pockets, a magazine communicating with the pockets, and a ball projecting device associated with the magazine, substantially as set forth.
7. A game apparatus comprising an up-standing and flat spiral race-way having a plurality of exit openings, passage-ways leading from said exit openings respectively, pockets at the terminal ends of said passage-ways, a releasable shelf closing the ends of said pockets, and a transparent cover and ball retaining plate overlying said race-way and the pockets, substantially as set forth.
8. A game apparatus comprising a spiral race-way having a tangentially disposed entrance and a radially disposed series of exit openings, a plurality of ball members, a plurality of pockets connected to communicate with said exit openings respectively, a magazine communicating with the pockets, and a ball projecting device associated with the magazine, a transparent cover plate overlying the race-way, the ball receiving pockets, and the magazine; and a coin controlled mechanism having operative connection with said pocket closing shelf and the
- with said exit openings respectively, a magazine communicating with the pockets, and a ball projecting device associated with the magazine and the tangential entrance-way, substantially as set forth.
9. A game apparatus comprising a coiled and upstanding race-way having a tangentially disposed entrance, a plurality of ball members, a plurality of pockets connected to communicate with said coil members respectively, a transparent cover plate overlying the race-way, the tangential entrance-way and said pockets; a magazine communicating with the pockets, and a ball projecting device associated with the magazine and the tangential entrance-way, substantially as set forth.
10. A game apparatus comprising a spiral race-way having a tangentially disposed entrance, a radially disposed series of exit openings formed in the respective coils of the race-way, said openings having indicia denoting scores of maximum and then decreasing values towards the peripheral edge of the race-way, and receiving pockets connected to communicate with said exit openings respectively, substantially as set forth.
11. A game apparatus comprising a flat spiral and upstanding race-way having a tangentially disposed entrance, a radially disposed series of exit openings formed in the respective coils of the race-way, said openings having indicia, the center opening denoting a zero score and the other openings denoting scores of maximum and then decreasing values towards the peripheral edge of the race-way, and vertically arranged receiving pockets connected to communicate with said exit openings respectively, substantially as set forth.
12. A game board comprising a suitable support, an upstanding and flat spiral race-way mounted thereon and having exit openings in its respective coils, a plurality of ball members, receiving pockets connected to communicate with the exit openings, a ball projecting device, and a transparent cover and ball retaining plate overlying the race-way, the ball entrance-way and the receiving pockets, substantially as set forth.
13. A game apparatus comprising a casing, an upstanding and coiled race-way closing the front of the casing, exit openings in the coils of the race-way, receiving pockets communicating with said exit openings respectively, a plurality of ball-members, a releasing shelf normally closing the pockets, a ball retaining bar, a magazine communicating with the pockets adjacent the ball retaining bar, a ball projecting device associated with the magazine, a transparent cover plate overlying the race-way, the ball receiving pockets, and the magazine; and a coin controlled mechanism having operative connection with said pocket closing shelf and the

ball retaining bar whereby to release the balls into the magazine for playing, substantially as set forth.

14. As an article of manufacture, a game apparatus part comprising a plate having formed on one face an upstanding flange providing a spiral race-way with the coils thereof lying in a common plane, a radial series of ball exit apertures in the coils of the spiral adapted to pass a ball traversing the race-way, ball receiving pockets, and channel-ways connecting said pockets with the ball exit apertures respectively, substantially as set forth.

15. As an article of manufacture, a game apparatus part comprising a plate formed with an upstanding flange providing a spiral race-way, ball exit apertures in the coils adapted to pass a ball traversing the race-way, ball receiving pockets, means providing channel-ways connecting said pockets with the respective exit apertures, all of said elements constituting a single unitary structure, substantially as set forth.

16. As an article of manufacture, a game apparatus part comprising a plate having formed on one face a spiral race-way with the coils thereof lying in a common plane, ball exit apertures in the coils adapted to pass a ball traversing the race-way, ball receiving pockets, and a magazine chamber, all of said elements comprising a single and unitary structure, substantially as set forth.

17. As an article of manufacture, a game apparatus part comprising a plate having formed on one face a spiral race-way with the coils lying in a common plane, ball exit apertures in the respective coils, ball receiving pockets each having an inlet aperture, and a magazine chamber communicating with said pockets, all of said elements being embodied in a single cast unit, substantially as set forth.

18. As an article of manufacture, a game apparatus part comprising a plate casting having formed on one face a spiral race-way with the coils thereof lying in a common plane, ball exit apertures in the coils of the spiral, ball receiving pockets each having an inlet aperture, and a channeled casting secured to the plate casting providing communication between the respective exit and inlet apertures, said elements constituting a single unitary structure, substantially as set forth.

55 In witness whereof, I have hereunto set my hand at Rochester, New York, this 14th day of October, A. D. nineteen hundred and thirty.

HOWARD J. PEO.
